UNITED STATES PATENT OFFICE.

WILLIAM FULTON FAIR, OF LONDON, ASSIGNOR TO ISAAC LOVELL BERRIDGE,
OF LEICESTER, ENGLAND.

BUTTONHOLE SEWING-MACHINE.

SPECIFICATION forming part of Letters Patent No. 500,708, dated July 4, 1893.

Application filed August 30, 1892. Serial No. 444,509. (No model.)

To all whom it may concern:

Be it known that I, WILLIAM FULTON FAIR, a subject of the Queen of Great Britain, residing at London, England, have invented new and useful Improvements in Sewing-Machines for Barring Buttonholes, of which the following is a specification.

This invention relates to improvements in that kind of button-hole finishing machines which form the bar of the button hole by a series of long stitches at right angles to the button hole and another series of stitches overlying the first series of stitches at right angles thereto.

For facility of description I will describe my improvements as applied to a lock-stitch sewing machine having a horizontal shaft for actuating the shuttle, such as a "Wheeler & Wilson" machine.

In carrying out the invention I provide a spring-clamp for holding the material with the button hole to be barred beneath the needle of the machine, the said clamp being adapted to feed the material in order to enable the needle to effect the stitching as above described. In order that the end of the button hole to be barred shall be placed in proper position beneath the needle of the machine, I provide the clamp with a projecting stop or guide onto which the button hole can be placed with the end to be barred bearing against it but, as the said stop would be in the way of the needle, I arrange on the clamp means for moving the stop out of the way as the clamp is closing to hold the material.

To impart the necessary movement to the clamp when applying the series of long stitches at right angles to the button hole, I connect to the said clamp a lever adapted to be operated by a cam, and for imparting the movement to the clamp necessary for applying the series of overlying stitches I connect another lever to the said clamp also adapted to be operated by a cam, the said cams being advantageously driven from the main shaft of the machine by suitable gearing. The feed necessary for applying the overlying stitches side by side is effected by another cam through the medium of the first named lever, the said cam being advantageously driven from the main shaft by a worm and wheel. Suitable means such as cams driven by the said worm gearing are employed for putting the levers

into and out of connection with their respective cams at the required times. One important advantage of this combination of parts for giving the necessary movements to the clamp is, that it affords the means of readily regulating the number and closeness of the stitches and so adapting the machine to different classes of work, by changing the worm and worm wheel as hereinafter described. Such a result I believe to be quite novel in this kind of machines.

To start the machine I provide a lever connected to a sliding spring-bar having a belt fork for throwing the driving belt from the loose onto the fast driving pulley. The said bar has two catches, one of which serves to engage with a lever to maintain the belt on the fast pulley the said lever being also adapted to engage with a projection on the worm-wheel hereinbefore mentioned so that, when the said wheel has completed a revolution, which is necessary to form the barring, it moves the said lever, thereby allowing the strap fork to move and throw the belt off the fast pulley. The other catch serves when the belt is thrown off as described to engage with a tooth on a disk on the main shaft to stop the machine when the needle is at its highest point.

To enable my invention to be fully understood I will describe the same by reference to the accompanying drawings, in which—

Figure 1 is an under side view of a "Wheeler & Wilson" lockstitch sewing machine having my improved button-hole barring mechanism applied thereto. Fig. 2 is an elevation of the same partly in section, the section being taken on the line 2, 2, Fig. 1. Fig. 3 is a sectional elevation of the head of the machine, the section being taken on the line 3, 3, Fig. 2. Fig. 4 is a plan view of the work-plate. Fig. 5 is a section on the line 5, 5, Fig. 3. Figs. 6 and 7 are under side views partly in section showing the arrangement of cams and levers for operating the work holding clamp. Figs. 8, 9 and 10 are sections on the lines 8, 8; 9, 9; and 10, 10 respectively of Fig. 1. Figs. 11 to 20 are views of the different cams detached. Fig. 21 is a view showing how the stitches forming the bar of a button hole are applied.

Similar letters of reference indicate corresponding parts in all the figures.

a is the bed-plate of the machine, *b* the

swan-neck, *c* the driving shaft carried in bearings *d*, *d*; *e* the cage or cradle for the hook or shuttle, and *f* a cam for operating the take-up *g*, all of which parts are of ordinary construction and require no further description.

- 5 *h* is my work holding clamp which comprises a sliding bar or plate *h'* adapted to slide upon the upper side of the work-plate and having attached to or formed integral 10 with it an arm *h²* designed with the bar *h'* to embrace the work-plate and to bear against the under side of the same, as shown most clearly in Fig 3, and also comprising a movable jaw, shown in the drawings as a spring- 15 arm *h³*, secured to the bar *h²* and having its free end serrated or roughened and adapted to hold the work between itself and a correspondingly serrated or roughened surface upon the bar *h'*. In the clamping ends of 20 the clamp are formed openings *h⁴*, through which the needle of the machine can pass, the said openings being of sufficient size to allow the necessary movements of the work holding clamp to take place relatively to the needle. 25 *i* is the stop which insures that the end of the button-hole shall be placed in the work holding clamp in proper position relatively to the needle of the machine. This stop is located in a groove in the bar *h'* and is attached to or formed integral with a bar *i'* sliding upon the bar *h'*, as shown most clearly in Fig. 5, screws *i²*, *i³* being passed through the bar *i'* for the purpose of guiding it. The opposite end of the bar *i'* to that carrying the 30 stop *i* is jointed to an arm *i³* attached to the spring-arm *h³*, as shown in Fig. 3, in such a manner that when the clamping end of the spring-bar *h³* descends to clamp the work the said bar *i'* will be moved so as to draw the 35 stop *i* to a position in which the needle cannot come into contact with it. When the clamp is again opened the stop *i* is moved back again ready for fixing the position of another button hole. The opening of the clamp is 40 effected by connecting the spring-arm *h³* to the lifting-bar *j* in the head of the machine by means of a chain *j'*. With this arrangement it will be understood that when the bar *j* is lifted by means of the lever *j²*, Fig. 2, the 45 clamp will be opened, and that when the bar *j* is again allowed to descend the clamp will 50 close and hold the work.
- 55 *k* is the lever through the medium of which the necessary movements of the clamp when applying the series of long stitches are effected, the said lever being pivoted to the base-plate at *k'* and connected to the arm *h²* of the clamp by means of a rod *k²*, which rod, as shown, is formed in two parts connected by 60 screws so as to make it readily adjustable as regards length. This lever *k* carries a pivoted arm *k³* provided at its free end with a roller *k⁴* and is operated by a cam *k⁵* secured to a bevel gear-wheel *k⁶* mounted upon a stud *k⁷* 65 and driven by a bevel-pinion *k⁸* upon the main shaft *c* of the machine. The gear-wheel *k⁶* and the pinion *k⁸* are shown in the draw-

ings in the proportion of two to one so that for two revolutions of the pinion *k⁸* the wheel *k⁶* makes one revolution. The cam *k⁵*, which 70 is shown in face and edge view, in Figs. 11 and 12 respectively, is so shaped that during one half of its revolution, that is, while the driving shaft makes a complete revolution and the needle moves down and up again, the 75 clamp will be in a position corresponding to one end of the long stitches and that during the other part of its revolution the clamp will be in a position corresponding to the other end of the long stitches, that is to say, 80 after each down and upward movement of the needle to form a stitch the clamp will be moved in one or the other direction, as indicated by the two arrows 1 in Fig. 4.

85 *k⁹* is a spring which, after the lever *k* has been moved by the cam in one direction, returns the said lever to its original position.

90 *l* is the lever by means of which the clamp is moved in the directions of the arrows 2 of Fig. 4 for the application of the overlying stitches, the said lever being pivoted at *l'* to the base-plate and at one end *l²* pivoted to the arm *h²* of the clamp while the other end is 95 acted upon by a spring *l³*.

100 *l³* is the cam by means of which this lever is actuated, the said cam, which is of substantially the same shape as the cam *k⁵* and which is shown in face and edge view respectively in Figs. 13 and 14, being secured to the cam *k⁵* and moving therewith. This cam *l³* acts 105 upon the lever *l* through the medium of the arm *l⁴* carrying the roller *l⁵* and acted upon by the spring *l⁶*, the said arm *l⁴* having formed integral with it a lever-arm *l⁷* for a purpose hereinafter described. With this arrangement it will be understood that, assuming the roller *l⁵* to be in contact with the periphery of the cam *l³*, the movement of the latter will cause the movement of the lever *l* upon its pivot *l'* and thereby move the work clamp in 110 the direction of the arrows 2 Fig. 4.

115 In the operation of the machine the clamp is first of all moved to apply the long stitches and then to apply the overlying stitches. It is therefore obvious that while the long stitches are being applied the roller *l⁵* of the lever *l* must be out of contact with its cam *l³* and during the time that the overlying stitches are being applied the roller *k⁴* of the lever *k* must be out of contact with its cam *k⁵*. Further it is necessary while applying the overlying stitches that the work clamp should be caused to travel in the required direction to cause the stitches to be applied side by side. In order to produce these different results I 125 provide three cams *m*, *n*, *o* secured to a worm-wheel *p* carried upon a stud *p'* and adapted to be driven by a worm *p²* upon the driving shaft *c* of the machine.

130 The cam *m* which is shown in face and edge view in Figs. 15 and 16 is designed to hold the roller *l⁵* out of operative contact with its cam *l³* during the time that the roller *k⁴* is in operative contact with its cam *k⁵*. This cam

m acts against a projection *m'* upon a lever *m²*, one end of which is pivoted at *m³* while the other end *m⁴* is adapted to bear upon the lever-arm *l⁷* of the arm *l⁴* in such a manner that when the high part of the cam *m* is in contact with the projection *m'* the lever *m²* will with its end *m⁴* press upon the lever-arm *l⁷* and hold the roller *l⁵* in the required position as in Fig. 6.

10 To insure that when the lever *m²* acts upon the lever *l⁷* of the arm *l⁴* the lever *l* shall remain stationary, the spring *l⁸* is made stronger than the spring *l⁶* so that the latter will yield and allow the necessary movement of the arm *l⁴*. To insure also that while the work clamp is being moved for the application of the long stitches it shall be in such a position (as regards its movement in the direction of the arrows 2, Fig. 4) that the needle when applying the overlying stitches shall enter the work at equal distances from the two sides of the said long stitches I provide in the arm *l⁷* a screw *l⁹* which when the roller *l⁵* is in the position shown in Figs. 1 and 6 will bear against the end of the lever *l* and so insure that the position of the work clamp shall be absolutely controlled by the high part of the cam *m*.

The cam *n* which is shown in face view and edge view respectively in Figs. 17 and 18 is designed to act upon a projection *n'* upon an arm *n²* pivoted to the base plate at *n³* and at one end acted upon by a spring *n⁴*, the other end being slotted or recessed to embrace the lever *k³* carrying the roller *k⁴*. When the high part of the cam *n* acts against the projection *n'* the lever *n²* will be lifted against the pressure of the spring *n⁴* in order to hold the arm *k³* so that its roller *k⁴* is out of operative contact with the cam *k⁵*, as shown in Fig. 7. When, however, the arm *n'* is in contact with the low part of the cam *n* the lever *k³* will drop sufficiently to place its roller *k⁴* in operative contact with the said cam *k⁵*, as shown in Fig. 6.

45 The cam *o* which is shown in face and edge view respectively in Figs. 19 and 20 is adapted to act against a projection *o'* (Figs. 6 and 7) upon the lever *k* and the difference between the highest and lowest parts of the cam *o* corresponds to the length of bar to be formed upon the button hole so that as the said cam *o* is rotated it will, by acting against the projection *o'*, move the lever *k* and consequently also the work-clip *h* the required distance.

55 The cams *m, n, o* are so arranged relatively to each other that the high part of the cam *m* operates against the projection *m'* of the lever *m²* during the time that the arm *n'* of the lever *n²* is in contact with the low part of its cam and vice versa, and that while the high part of the cam *n* is in contact with the projection *n'* of the lever *n²* and the lower part of the cam *m* in contact with the projection *m'* the part of the cam *o* of gradually increasing diameter will be acting upon the projection *o'* to move the work clip *h* to cause the stitches to be applied side by side.

In order to regulate the number of stitches in the bar and the number and closeness of the overlying stitches it is only necessary to provide worm-wheels such as *p* with a greater or less number of teeth and to provide corresponding worms so that the needle will make a greater or less number of up and down movements during one rotation of the worm-wheel. Thus by changing the worm and worm wheel the number and closeness of stitches required for different classes of work can be obtained. In all prior machines no such provision for adaptation was secured, and it is an important feature of my present arrangements that the cams *k⁵* and *l⁷* with the parts which they operate are so arranged in relation to the cams *m, n* and *o* and the worm *p²* and the worm-wheel *p* that this adaptability is secured.

q is the belt or driving pulley fixed to the shaft *c*, and *q'* is a loose pulley upon which the belt runs during the time that the work is being introduced into and removed from the work holding clamp. *q²* is the belt fork which serves to transfer the belt *q³* from one pulley to the other. This fork is secured to a rod *q⁴* sliding in guides at *q⁵, q⁶* in the under side of the bed-plate *a*, as shown in Figs. 1 and 10. Upon this rod *q⁴* is a collar *q⁶* and between this collar and one of the guides *q⁵* is a spring *q⁷* which tends to move the fork into the position for the belt to run upon the loose pulley *q'*. In order to move the fork *q²* to transfer the belt from the loose to the fast pulley I extend the shaft *r*, Figs. 2 and 10, (upon which shaft *r* the take-up *g* is free to oscillate) through the side of the swan-neck *b* and upon this projecting end I fix a lever *s*. I also fix to the shaft *r* an arm *t* which acts against the collar *q⁶* in such a manner that when the lever *s* is depressed the said collar and with it the rod *q⁴* will be moved against the pressure of the spring *q⁷*. To retain the rod *q⁴* in this position so that the belt will run upon the fast pulley I attach to the said bar a catch or collar *u* having an inclined or conical surface adapted, when the said rod *q⁴* is moved to shift the belt onto the fast pulley, to impinge against one end of a lever *v*, the other end of which is pivoted at *v'*, Figs. 1 and 9, and which is acted upon by a spring *v²* in such a manner that when the collar *u* impinges against the free end of the said lever *v* it will cause the same to descend, the spring *v²* after the collar has passed drawing the said lever behind the collar so as to prevent the rod *q⁴* from moving back again.

In order that, when the bar is finished, the machine shall be automatically stopped, I fix upon the worm-wheel *p* a lug or projection *x* designed at each revolution of the said wheel to act upon an arm *y* upon the lever *v* in such a manner as to lower the said lever *v* sufficiently to disengage the free end thereof from the collar *u*, thereby allowing the bar *q⁴* to be moved back under the action of the spring *q⁷*. From the description of the cams *m, n, o*

hereinbefore described it will be understood that the worm-wheel p makes one revolution during the formation of each bar; the said projection x must therefore be placed in such a position upon the said wheel that it only acts upon the arm y when the bar is completed. To insure that when the machine is thus stopped the needle shall be in its uppermost position clear of the work, I form upon the cam f a tooth or projection z , and so locate it thereon relatively to the movements of the needle-bar, that when the bar q^4 moves to the position to shift the belt onto the loose pulley, it impinges against the collar q^6 which is at the same time moved into its path.

In order to minimize the concussion between the tooth z and the collar q^6 the latter is provided with a buffer spring z' .

z^2 is a spring detent pawl which engages with a notch in the periphery of the cam f to prevent the machine from being worked in the wrong direction.

The operation of the machine hereinbefore described is as follows:—Assume a piece of work to be placed in the work-holding clamp h as hereinbefore described and assume the belt to be running upon the loose pulley q' and the roller k^4 to be in operative contact with its cam k^5 , as shown in Fig. 1. The lever s is now depressed in order to shift the belt onto the fast pulley whereby motion will be imparted to the needle and, at the same time, the cam k^5 being rotated from the driving shaft c , a to-and-fro motion will be imparted to the work-holding clamp in order to apply the long stitches as indicated in Fig. 21. When a sufficient number of long stitches has been applied, which number is regulated by the shape of the cam n , the said cam acts upon the lever n^2 to shift the roller k^4 out of contact with the cam k^5 and at the same time the cam m has moved so far as to allow the roller l^5 to make contact with its cam l^3 under the action of the spring l^6 so that the necessary movement is applied to the work-holding clamp for the application of the overlying stitches, the said clamp being at the same time caused to travel by means of the cam o in order to lay the said overlying stitches side by side also as indicated in Fig. 21. By the time a sufficient number of overlying stitches has been applied the wheel p has traveled so far that the projection x thereon comes into contact with the arm y of the lever v whereby the latter is lowered to disengage the said lever from the catch or collar u so that the spring q^7 moves the belt fork q^3 to throw the belt onto the loose pulley; the collar q^6 being at the same time thrown into the path of the tooth z upon the cam f whereby the latter is stopped in the required position.

In the foregoing description I have referred to the starting of the machine as being effected through the medium of a hand-lever; if desired, however, this operation may be ef-

fected through the medium of a foot-lever. In this case I form the arm t with an extension t' , as indicated by dotted lines in Fig. 2, and to the said extension I connect a chain t^2 which is suitably attached to a pedal. 70

Having now particularly described and ascertained the nature of my said invention and in what manner the same is to be performed, I declare that what I claim is—

1. The combination in a sewing-machine for 75 finishing button-holes of the work-holding clamp, the clamp traversing cams, the levers intermediate such clamp and cams, the three cams $m. n. o.$, a changeable worm-wheel p , to which they are secured, the stud p' which carries said wheel, and worm p^2 , upon the driving shaft of the machine, and serving to drive said wheel, all substantially as shown and described.

2. The combination with stitch-forming 80 mechanism of the clamp traversing cams k^5 and l^5 , the governing cams $m. n. o.$, the levers $m^2. n^2. k$, operated thereby, and the change wheel $p. p^2$, with the driving slot c , gear-pinion k^3 , and gear k^6 , and whereby by changing 85 of the wheels $p. p^2$, the number and closeness of the stitches may be regulated substantially as described.

3. In a button-hole finishing machine, the combination with the work-holding clamp of 90 a guide plate h' , a stop or guide such as i , moving in such plate, means substantially as set forth for moving such guide, arm i^3 , and spring h^3 , the combination being and operating substantially as set forth. 95

4. In a button-hole finishing machine having a work-holding clamp adapted to be moved in one direction to apply a series of long stitches, and then in another direction to apply a series of overlying stitches, the combination with the said clamp, of lever k , and its pivoted arm k^3 , and operating cam k^5 , lever l , its pivoted arm l^4 , and its operating cam l^3 , of the peripheral cams $m. n.$ on worm-shaft p' , and whereby said arms are alternately moved into and out of contact with the main operating cam, substantially as described. 105

5. In a button-hole finishing machine, having a work-holding clamp applied to be operated as described, and having a sliding bar and a belt-shifting fork fixed thereto, the combination therewith of a collar, q^6 a cam or disk upon the main driving shaft provided with a tooth adapted when the said bar is 110 shifted, to impinge against said collar which is at the same time thrown into the path of the said tooth, substantially as and for the purpose described. 115
